UNITED STATES PATENT OFFICE.

JOHN HENRY CROSKEY, OF DUNKIRK, INDIANA, ASSIGNOR TO THE BEATTY-
BRADY GLASS COMPANY, OF SAME PLACE.

DESIGN FOR A PITCHER.

SPECIFICATION forming part of Design No. 29,364, dated September 20, 1898.

Application filed August 22, 1898. Serial No. 689,369. Term of patent 14 years.

To all whom it may concern:

Be it known that I, JOHN HENRY CROSKEY, a citizen of the United States, residing at Dunkirk, in the county of Jay and State of Indiana, have invented and produced a new and original Design for Pitchers and Similar Articles, of which the following is a specification, reference being had to the accompanying drawings, forming part thereof.

10 In the drawings my new design is illustrated in views of the several sides of the pitcher, Figures 1 and 2 being the opposite sides, and Figs. 3 and 4, respectively, show the mouth and handle sides. Fig. 5 represents the pitcher in perspective, looking at the bust.

15 The distinctive features of my new design are a bust and a battle-ship, arranged and disposed with which are grouped emblematic representations, making a naval design commemorating the battle of Manila. The representations are formed in bas-relief, the bust being disposed on one side of the pitcher and the battle-ship on the other side. Encircling the bust is a wreath, and at one side is an artillery field-piece, while between the latter and the battle-ship, at the handle side, are arranged the flags of the United States and the Republic of Cuba, with crossed staffs.

At the mouth side of the pitcher is a representation of crossed cannon. On one side the crossed cannon are flanked by the representation of an eagle with spread wings surmounting the bust. On the other side of the crossed cannon is a representation of the flag of the United States admiral.

20 Disposed around the pitcher below the bust and the battle-ship are pyramidal banks of cannon-balls, and between two of these banks rises the bust upon the insignia of rank, being the illustration of an anchor and two stars. Above the field-piece is an illustration of signal-flags. Between the banks of cannon-balls are disposed representations of sheathed swords, crossed guns, and the "Red Cross." 45 Above the field-piece is an illustration of signal-flags. A shell surmounts each bank of cannon-balls.

25 Having described my invention, what I claim as new, and desire to secure by Letters 50 Patent, is—

The design for a pitcher or similar article substantially as herein shown and described.

JOHN HENRY CROSKEY.
